UNITED STATES PATENT OFFICE.

JAMES T. HOAL, OF BATON ROUGE, LOUISIANA.

LOUVERED VENTILATOR.

Application filed October 4, 1927. Serial No. 223,980.

This invention relates to improvements in louvered ventilators, having for an object to provide a ventilator of the type indicated wherein a novel construction of louver slat is employed in series arrangement and such relative disposition as will ensure ample ventilation and a positive exclusion of the elements from a room, space or other area whose wall or walls are equipped therewith, the said slat being formed with baffle or impedimenta upon said marginal and intermediate portions which, with arrangement of a plurality of such slats in overlapping relationship, will serve as a water trapping means, shunting the water therefrom and consequently preventing its passage into the equipped room or other area.

It is an equally important object of the invention to provide a louver slat wherein the arrangement of baffle means thereupon is such that the slat may be economically manufactured and will be materially reinforced so as to impart the maximum of durability and strength to a ventilator construction including the same.

Other objects of the invention will be in part obvious and in part pointed out hereinafter.

In order that the invention and its mode of operation may be readily understood by those skilled in the art to which it appertains, I have in the accompanying illustrations, and in the detailed following description based thereupon, set out one possible embodiment of my invention.

In these drawings:

Figure 1 is a front elevation of the improved ventilator.

Figure 2 is a vertical or longitudinal section through the same, and

Figure 3 is a vertical transverse section through one of the louver slats.

Having more particular reference to the drawings, in connection with which like characters of reference will designate corresponding parts throughout, the invention may be stated to comprehend a substantially rectangularly shaped frame 1 provided with jamb and sill portions, the outer marginal part of said frame being flanged entirely thereabout as is indicated by the numeral 2 whereby to facilitate the positioning and fixing of said frame in the masonry or other elements constituting a wall construction.

Disposed across or transversely of the frame 1 are a plurality of louver slats design-

nated for clarity herein by the numerals 3, 4 and 5, said louvers being arranged within the frame 1 in inclined and relatively spaced overlapping relationship as is shown in the Figure 2, the opposite marginal portions of the louver slats 5 being extended into substantially parallelism whereas the forward portions of the louver slats 3 and 4 are correspondingly arranged while the upper or inner portions thereof are engaged or joined, by suitable means, to the inner side of the top of the frame 1, as is well shown in the Figure 2. By this inclined positioning and relative overlapping of the louver slats, it will be understood that upwardly directed or inclined passage ways will be provided between each thereof, the lower ends of such passage ways opening onto or adjacent the forward side of the ventilator frame whereas the remaining or inner extremities thereof open onto the inner side of such ventilator frame. Because of this, it will be understood that the louvers 3, 4 and 5 will act as baffle means or impedimenta to the passage of water through the ventilator construction into a room or other area equipped therewith.

The louvers 5 are each constructed of single pieces of sheet metal or other suitable material, such as conditions or preference may dictate, said louvers each having their opposite marginal portions provided with right angularly formed and inwardly disposed baffles 6 which, as will be noted, are arranged at obtuse angles with respect to the body portion of their respective louver slats; whereas the intermediate portions of each of said louver slats has stamped or otherwise formed therein intermediately positioned and longitudinally extending baffles 7, there being preferably one of these baffles to each of said louver slats and said baffle being transversely curved upon itself as is shown in the Figures 2 and 3, one side of said baffle 7 joining with the adjacent portion of the louver slat whereas the opposite side of said baffle joins with the remaining side of the slat, effecting, in this way, an offsetting of said oppositely disposed portions of the slats so that they are arranged in different planes as is shown in the Figure 3. Furthermore, it will be noted that because of the transverse curving of the baffles 7 in each of the louver slats 5, the inner extremities of the walls thereof will be disposed in slightly overlapping relationship to the adjacent and

joining extremity of the upper side of said slat, thus giving a greater area of impedance to the baffle that the same will serve to positively prevent the passage of hail, 5 rain or snow through the passage ways of the ventilator construction.

The louver slat 4 has the upper portion thereof cut away, as is shown in the Figure 2, that a proper connection or joinder of 10 the same may be had with the inner side of the ventilator frame top, as is the major portion of the louver slat 3, thus leaving to the slat 4 its lowermost right angularly formed baffle 6 and the intermediate longitudinally disposed baffle 7, and to the louver slat 3, its lowermost right angularly formed baffle 6. In this connection, it is timely to 15 note at this point that each of said louver slats 3, 4 and 5 are arranged, as hereinbefore 20 stated, in inclined relative overlapping relationship so as to provide an effectual impedance to the passage of certain elements through the ways of the ventilator construction into a room or other space equipped with 25 the device.

A slat 8 is preferably arranged in the lower portion of the ventilator frame 1, as is shown in the Figure 2, said slat being outwardly inclined toward the normally inner 30 side of the device.

Various means may be employed for securing the louver slats 3, 4 and 5 and the closure slat 8 in fixed or secure positioning with respect to the rectangular frame 1, it 35 being practicable that the said elements be soldered to the adjacent or contacting portions of the jamb heads and sills of said frame.

By reason of the relative positioning and 40 arrangement of the louver slats 3, 4 and 5 in the ventilator frame 1, it will be understood that the lowermost and outwardly disposed baffles 6 thereof, in being disposed in planes below or partially below those 45 planes in which the intermediately arranged baffles 7 are positioned, will function as effectual means for avoiding or preventing the passage of certain elements thereby and through the adjacent ventilator ways of the 50 construction into a room or other space equipped therewith, whereas the transversely curved and intermediately positioned longitudinal baffles 7 will afford an effectual impedance or series of impediments to these 55 elements or to such portions of those elements as pass the lowermost and outwardly disposed baffles 6, trapping the same because of their transverse curvature and shunting them downwardly and from without the ventilator construction. The upper or innermost baffles 6 upon the louver slats 5 will serve as a final check or impedance to such 60 of those elements as may pass the previously discharged baffles 6 and 7, strapping the 65 same before they are discharged or delivered

into a room or space equipped with the construction and by reason of the downwardly inclined positioning of the louver slats, causing such elements to be shunted from the construction.

Because of the particular arrangement of the passage ways between the louver slats 3, 4 and 5, it will be furthermore understood and appreciated that the construction will serve as an effectual means to permit effectual 70 means to permit of ample ventilation or air passage into an equipped room or space, such air passage taking the form of air currents which flow through the ways between the various louver slats, without detrimental 75 impedance or baffling from the baffles 6 and 7, aforesaid.

While I have hereinbefore disclosed one particular form of ventilator frame, it of course will be readily understood by workers 80 skilled in the art that the shape and size of this frame may be varied in many respects, such as conditions or preference may dictate, furthermore, that the number of louver slats designated by the numeral 5 may be increased or decreased to accord with the particular size of ventilator frame to be equipped therewith, while it may become necessary, because of the peculiar shape and size of a modified form of ventilator frame, to cut 85 away or remove other portions of the louver slats, than those indicated in the present embodiment of the invention by the numerals 3 and 4.

I claim:

1. A louver slat having the intermediate portion of the same disposed at substantially right angles to the body thereof and transversely curved upon itself, said intermediate portion extending longitudinally throughout 100 the length of the slat, and inwardly disposed cross sectionally right angularly formed baffles upon and extending throughout the longitudinal marginal portions of said slat.

2. A louver slat having a trough-like body 105 portion formed intermediately of the same and disposed longitudinally thereof throughout its length and discharging downwardly, those portions upon the opposite sides of the trough-like portion being of approximately 110 the same width and in different planes.

3. A louver slat having a trough-like portion formed longitudinally of the intermediate part thereof and opening downwardly, those portions of said slat upon the opposite sides of the trough-like portion being of approximately 115 the same width and arranged in different planes, and inwardly disposed cross sectionally right angularly shaped baffles upon and extending throughout the longitudinal marginal portions of 120 said slat.

4. A louver ventilator including a frame, a series of relatively spaced louver slats carried by and disposed across the frame in rela- 125 130

tively inclined and overlapping relation, certain of said slats having a trough-like downwardly discharging intermediate portion formed therein, those portions of said slats upon the opposite sides of the trough-like portion being of approximately the same width and arranged in different planes but in substantial parallelism, and inwardly dis-

posed cross sectionally right angularly shaped baffles formed upon and extending longitudinally throughout certain of the marginal portions of the said slats. 10

It witness whereof I have hereunto set my hand.

JAMES T. HOAL.
